UNITED STATES PATENT OFFICE.

LESTER ROTHSCHILD, OF CINCINNATI, OHIO.

MACHINE FOR FINISHING CLOTH.

1,184,026.

Specification of Letters Patent. Patented May 23, 1916.

Application filed August 15, 1914. Serial No. 856,900.

To all whom it may concern:

Be it known that I, LESTER ROTHSCHILD, a citizen of the United States of America, and resident of Cincinnati, county of Hamilton, State of Ohio, have invented certain new and useful Improvements in Machines for Finishing Cloth, of which the following is a specification.

The shrinking process to which cloth is subjected before it is made into garments leaves most kinds of cloth in a rough and unfinished condition. The problem of removing this condition without stretching the cloth has been one the solution of which has baffled the trade, heretofore. This is particularly the case with cloths of loose weave or of a texture which makes them subject to stretching.

The object of my invention is to provide a machine which will remove the rough and unfinished appearance leaving the cloth with a high smooth finish, and with what the trade terms a "soft handle" without stretching it. This object is attained by the means described in the specification and illustrated in the accompanying drawings in which:

Figure 1 is a side elevation of a machine embodying my invention. Fig. 2 is a longitudinal sectional view thereof, taken upon line 2—2 of Fig. 3. Fig. 3 is an end elevation thereof.

The machine embodying my invention comprises a steam cylinder, a conveyer sheet, which is to be fed upon the steam cylinder, and to engage the cloth to be treated and to wind it upon the cylinder between the layers of the conveyer sheet, a means for holding the conveyer sheet under tension while it is being wound upon the steam cylinder, and a guide roll for the cloth, which will feed the cloth in a flattened condition to the conveyer sheet to be carried forward by it and wound with it upon the steam cylinder.

Referring to the parts, the conveyer sheet A is made preferably of canvas, and is to be stored upon the roller B which is journaled in the frame D of the machine. Adjacent to one of the journals of the shaft B a friction bar B' is pivoted upon the frame and is provided with a weight B² which holds the friction bar in contact with the shaft of the roll B, to retard the rotation thereof and put the conveyer sheet under tension when it is being wound upon the steam cylinder. The steam cylinder E is journaled in the frame, and has in its walls

a series of radial holes e. Between the roll B and the steam cylinder E a series of rolls b, b', b² are journaled in the frame, and afford means for assisting in keeping the conveyer or leader sheet taut. The feed roll F, upon which the cloth to be finished is wound, is journaled like-wise in the frame, and between it and the steam cylinder guide rolls f, f' are journaled.

Journalled in the frame is the driving shaft G upon which pulleys g and g' are loosely journaled. Pulleys g and g' are provided with clutch teeth, adapted to be engaged by clutches g² and g³ which are splined upon the shaft and are provided with levers g⁴ and g⁵ for throwing them into firm engagement with pulleys g and g'. Pulley g is connected by a belt g⁶, with a pulley secured upon the shaft of the steam cylinder E. Pulley g' is connected by a belt g⁷ with a pulley secured upon the end of the shaft of the roll B. Adjacent to the sheet roll B elongated journal slots a are formed by L-shaped irons a² for the receptions of the journals of a roller H, which bears loosely upon the periphery of the roller B.

In operation the cloth to be finished is wound upon the feed roll by applying a manually operated crank to the square end f⁵ of its shaft. Clutch g² being thrown into engagement with pulley g rotation is conveyed from the main shaft G to the steam cylinder E and the conveyer sheet B, then starts to feed under tension upon the steam cylinder. The operator then brings the forward edge of the cloth to be finished over the guide rolls f and f' and inserts said end between the conveyer sheet A and the steam cylinder E. The guide rolls f and f' keep the cloth to be finished spread transversely so that it is fed smoothly on to the steam cylinder, between the layers of the conveyer sheet, which being held taut flattens the cloth smoothly between its layers as it is fed upon the steam cylinder, but without subjecting it to any longitudinal strain. After the cloth to be finished has been fed on to the steam cylinder, steam is admitted thereto, escapes through the holes e and permeates the cloth. The steam is thus permitted to permeate the cloth for a few minutes, the length of time depending upon the character of the cloth. Then the steam is turned off and the cloth is permitted to cool somewhat while remaining upon the cylinder. Then the clutch g³ is thrown into engagement with the pulley g',

which rotates the feed roll B and starts to rewind the conveyer sheet thereon. The end of the cloth is placed around the roll H which is rotated by its being held in contact 5 with the feed roll B, by its weight. As the cloth accumulates upon the roll H its journals rise in the guide ways a. After the cloth is rewound upon the roll H it is lifted 10 from the guide ways a and removed from the machine.

What I claim is:

In a machine for finishing cloth, the combination of a frame, a feed roll for the cloth freely journaled in the upper part of 15 the frame, a second feed roll for a conveyer sheet journaled in the frame beneath said first feed roll, means mounted upon the frame for retarding the rotation of the second feed roll, a perforated steam cylinder

journaled in the frame below the said first feed roll, a conveyer sheet upon the second feed roll, tension rolls between the steam roll and the second feed roll over which the sheet is led to the steam cylinder, guide rolls located between the first feed roll and the steam cylinder upon which cloth from the feed roll is adapted to rest in being led between the perforated steam cylinder and the conveyer sheet, means for admitting steam to the steam cylinder, and means for rotat- 20 25 30 ing the steam cylinder.

In testimony whereof, I have hereunto subscribed my name this 11th day of Aug., 1914.

LESTER ROTHSCHILD.
